DESIGN FOR A SPEAR

Leo D. Goddeyne, Bay City, Mich.

Application March 16, 1938, Serial No. 75,868

Term of patent 7 years

To all whom it may concern:

Be it known that I, Leo D. Goddeyne, a citizen of the United States, residing at Bay City, in the county of Bay and State of Michigan, have invented a certain new, original, and ornamental Design for Spears, of which the following is a specification, reference being had to the accompanying drawing, forming a part thereof.

In the drawing—

Fig. 1 is a front elevational view of a spear showing my new design.

Fig. 2 is a sectional view taken on the line 2—2 of Fig. 1.

What I claim is:

The ornamental design for a spear, as shown.

LEO D. GODDEYNE.
